ARRANGEMENT FOR FUEL INJECTION IN A
FREE-PISTON UNITDonald E. Meitzler, Manchester, Conn., assignor
to United Aircraft Corporation, East Hartford,
Conn., a corporation of Delaware

Application August 23, 1944, Serial No. 550,895

5 Claims. (Cl. 230—56)

1

This invention relates to an injection system for free-piston units and particularly to an arrangement by which the system may be filled with fuel prior to starting the unit.

Starting a free-piston unit having opposed pistons reciprocating in an engine cylinder may be effected by moving the pistons into starting position in which they are spaced from the inner end of the piston stroke and then causing the pistons to move rapidly toward each other on a starting stroke to cause compression ignition of the fuel injected into the cylinder during the starting stroke. To assure satisfactory fuel injection the injection system, which is generally actuated by the restraining linkage which connects the pistons, must be filled with fuel prior to the starting stroke. A feature of this invention is an arrangement by which to assure filling of the injection system.

The injection pump may be the type in which the pump plunger closes the filling and relief ports during the pumping stroke in order to trap in the cylinder fuel to be pumped to the nozzle. A feature of this invention is the arrangement of the starting system so that when the pistons are in starting position the filling port will be uncovered and the injection system will fill with fuel.

If the injection system is the accumulator type the pump plunger may have a venting groove which connects the accumulator chamber to a vent port in one position of the plunger to assure removal of all air from the chamber. A feature of the invention is the arrangement of the pump and starting system so that the accumulator chamber is vented while the pistons are in starting position.

Other objects and advantages will be apparent from the specification and claims, and from the accompanying drawings which illustrate an embodiment of the invention.

Fig. 1 is a sectional view through the free-piston unit.

Fig. 2 is a sectional view of the restraining linkage showing the cam for actuating the injection pump.

Fig. 3 is a sectional view of a part of the starting system.

Fig. 4 is a sectional view of the injection system.

Fig. 5 is a sectional view of the injection system with the plunger in another position, and showing the actuating means.

The unit shown includes an engine cylinder 10 having reciprocating pistons 12 and 14 to

2

which compressor pistons 16 and 18 in cylinders 20 and 22 are integrally connected. Sleeves 24 and 26 attached to the compressor pistons complete the reciprocating piston assemblies. The sleeves in combination with stationary pistons 28 and 30 form air spring cylinders.

The piston assemblies are moved apart by the burning of fuel injected into engine cylinder 10 through one or more nozzles 32. Air compressed 10 in the air spring cylinders on the power stroke returns the piston assemblies. The assemblies are always maintained at equal distances from the center of the engine cylinder by linkage, Fig. 2, which may include racks 34 and 36 extending from the piston assemblies and meshing with a pinion 38 on a shaft 40.

Intake manifold 42 which extends around the compressor and engine cylinders conducts air to intake valve 44 in the heads of the compressor 20 cylinders through which air alternately enters opposite ends of the cylinders. The compressed air leaves the cylinders through discharge valves 46, also at opposite ends of the compressor cylinders, and passes into a central scavenging chamber 48 and end chamber 50 and 52. These chambers may be interconnected by a scavenging manifold, not shown.

Compressed gas from the scavenging chambers enters engine ports 54 and 56 which are uncovered by pistons 12 and 14 at the end of the power stroke, thereby permitting air to be blown through the engine cylinder. Gas in the engine cylinders is discharged through exhaust ports 58 into exhaust manifold 60.

35 The injection device is actuated from a cam 62, Figs. 2 and 5, on the same shaft 40 that carries the pinion 38. A shoe 64 engages cam 62 and is mounted in a block 66 movable between guides 68. Block 66 engages the end of a plunger 10 reciprocating in a bore 72 in a casing 74. With the plunger in the position shown in Fig. 5 before it begins its injection stroke, an inlet port 76 admits fuel to the end of bore 12. During the injection stroke the plunger closes port 76 45 and fuel is forced by the plunger into accumulator chambers 18 and 80, Fig. 4, through a groove 82 in a valve 84 and a cross passage 86 which connects the chambers. Valve 84 is slidable in a bore 88 in a ring 90 in the casing.

50 While fuel is being forced into the accumulator chambers valve 84 closes a passage 92 which connects passage 86 with the discharge nozzle 32. One end of valve 84 is in line with a seat 96 at the end of passage 92 and is held on the 55 seat by the pressure of fuel on the opposite end

of the valve during the injection stroke of the plunger. Groove 82 permits a throttled flow of fuel past the valve into the accumulator chambers. The end of valve 84 remote from seat 96 engages a seat 98 at the end of bore 88 to close the end of groove 82.

Air in the accumulator chambers 78 and 80 is vented through a passage 100 in casing 10 which connects with the upper end of chamber 78. The opposite end of the passage forms a port 102 in bore 12 opposite a relief or vent port 104. Plunger 70 has a groove 106 which at a predetermined point during the plunger stroke connects ports 102 and 104 so that air in the accumulator chambers 78 and 80 is discharged through passage 100. Discharge of fuel through passage 92 to nozzle 32 may be controlled by a check valve 108 held against a seat 110 by a spring 112. When accumulator valve 84 moves to open passage 92 fuel pressure opens the check valve 108 and flows through a groove 114 to one or more openings 116 in the end of nozzle 32.

During the pumping stroke of the plunger the head of the plunger closes inlet port 76 and port 102 is closed by the edge of groove 106. As the plunger continues its pumping stroke with port 76 closed the pressure of fuel in chambers 78 and 80 is raised until port 76 is uncovered by groove 106. Fuel from the space at the head of the plunger is then discharged through a passage 118 in the plunger extending from the head of the plunger to groove 106. The resulting reduction of pressure in the plunger bore causes valve 84 to move endwise into the position of Fig. 4, thereby opening passage 92 for the discharge of fuel from the accumulator chambers through the nozzle. Accumulator valve 84 is again moved to engage seat 96 when the plunger begins its next pumping stroke.

During the return stroke of plunger 70 groove 106 connects ports 102 and 104 and the pressure remaining in chambers 78 and 80 forces out through passage 100 any air that may have been trapped in the chambers.

In order that the above described injection system may be entirely filled with fuel before the free-piston unit is started, the starting system is arranged so that when the pistons are moved into starting position the plunger 70 will have been moved into the position shown in Figure 5 in which port 76 is uncovered and ports 102 and 104 are connected so that fuel may flow through the pump to fill the accumulator chambers, the latter being vented to permit escape of any air therein. As shown in Fig. 3 the starting system includes an arrangement by which the pistons may be moved substantially into the position of Figures 1 and 3 adjacent the outer end of the piston stroke. The piston moving means is shown in Figure 3 for the piston assembly including the compressor piston 16. A similar piston moving means would be provided for the other piston assembly.

Extending from piston 16 are spaced tubes 120 and 122 forming at their outer ends an annular plunger 124 fitting between stationary spaced tubes 126 and 128. The stationary tubes are supported in a block 130 which may be integral with a part of the wall of the central scavenging chamber 48. Gas under pressure is admitted to the space between the tubes 126 and 128 through a passage 132 and a connecting conduit 134. This fluid acts on plunger 124 to move the piston 16 into the position shown. The position to which the piston is moved is determined by a vent 136.

provided in tube 128 so that the piston assembly will not be moved further toward outer end position than the position shown in Figure 3.

This starting position is so arranged that when the piston 16 is in starting position the actuating cam 62 for the fuel injection device will be in the position of Figures 2 and 5 so that the fuel may enter port 76 and fill the entire accumulator system. The remainder of the starting system, which not being a part of the starting system is not shown, may be the type described in the copending application of Meitzler, Serial No. 495,927, filed July 23, 1943, now patent No. 2,439,482, or in the copending Cooper application Serial No. 550,875, now patent No. 2,434,453. Dot-dash lines 138, Fig. 2, and 140, Fig. 5, represent similar positions of cam 62 in the two figures.

In operation, the free-piston unit having been stopped with the pistons in any position, gas under pressure is supplied to passage 132 thereby acting on plunger 124 and moving the piston assemblies into the position shown in Fig. 1. Fuel under pressure is supplied to filling port 76 and when the piston assemblies reach the positions shown, the linkage shown in Fig. 2 will have moved cam 62 into the position of Fig. 5 allowing plunger 70 to reach the position of this figure in which filling port 76 is uncovered by the end of the plunger and vent port 104 is connected by groove 106 with passage 100. Fuel under pressure thus enters the bore 72 through port 76 to fill said bore. Fuel from the bore flows past valve 84 into chambers 78 and 80, and any air in the chamber is forced out through passage 100, the passage 84 entering, as above stated, the upper end of the chamber 78. The fuel pump is thus filled with fuel, and when the piston assemblies are moved together by the starting system, on the starting stroke, the fuel will be injected through the nozzle 32 into the engine cylinder. With a delivery of fuel assured on the starting stroke, the free-piston unit will start dependably on the first operation of the starting system.

It is to be understood that the invention is not limited to the specific embodiment herein illustrated and described, but may be used in other ways without departure from its spirit as defined by the following claims.

I claim:

1. A free-piston unit including, a piston, an engine cylinder in which the piston reciprocates, pump means responsive to the piston reciprocation for supplying fuel to said engine cylinder, said pump means including a casing having a filling port, a plunger reciprocating in said casing and movable in response to reciprocation of the piston for covering and uncovering the port, said engine piston having a starting position from which it is moved in starting the unit, and means interconnecting said piston and the plunger by which the plunger is reciprocated, said interconnecting means supporting the plunger in a position to uncover said filling port when the piston is in starting position, in combination with a starting system and means forming a part of said system for moving said piston into said starting position.

2. In a free-piston unit, a piston, an engine cylinder in which the piston reciprocates, pump means responsive to the piston reciprocation for supplying fuel to said engine cylinder, said pump means including a casing having a filling port communicating with a fuel supply, and a plunger covering said port during a part of its stroke, and connected to and movable in response to

piston movement to cover and uncover the port, in combination with a starting system, and means forming a part of said system for automatically moving said piston into a starting position and causing the plunger to move to a position to uncover the filling port when said piston is in said starting position.

3. In a free-piston unit, a piston, an engine cylinder in which the piston reciprocates, pump means responsive to the piston reciprocation for supplying fuel to said engine cylinder, said pump means including a casing having a filling port, and a plunger movable in response to piston movement and uncovering said port during a part of its stroke, an accumulator chamber into which fuel under pressure is pumped by said plunger, said plunger also having means for venting air from the chamber during the part of the stroke when the filling port is uncovered, in combination with a starting system and means forming a part of said system for moving said piston into a position to cause the plunger to move to a position to uncover the filling port and to vent said chamber prior to starting the unit.

4. In a free-piston unit, a piston, an engine cylinder in which the piston reciprocates, pump means responsive to the piston reciprocation for supplying fuel to said engine cylinder, said pump means including a casing, a plunger reciprocating in said casing, said casing having a filling port connected to a fuel supply, and an accumulator chamber into which fuel under pressure is pumped by said plunger, said plunger having means for venting air from said chamber in one part of its stroke, in combination with a starting system, and means forming a part of the starting system for moving said piston into a starting position and thereby moving the plunger into a position in which the chamber is vented.

5

5. A free-piston unit having opposed pistons, an engine cylinder in which the pistons reciprocate, a linkage connecting the pistons, pump means including a casing, a reciprocating plunger in said casing actuated from said linkage for supplying fuel to said engine cylinder, said casing having a filling port connected to a supply of fuel, and a vent port both adapted to be uncovered during a part of the plunger stroke to permit the filling of the pump and the escape of air in the pump, said pistons having a starting position from which they are moved in starting the unit, said linkage, when the pistons are in starting position, causing the plunger of said pump means to assume a position in which the ports are uncovered so that the pump may be automatically filled with fuel and the air vented therefrom, in combination with a starting system and means forming a part of the system for moving said pistons automatically to said starting position.
